TILE WALL UNIT FOR SWIMMING POOLS

Raymond J. Stewart, Miami, Fla.

Application February 11, 1953, Serial No. 23,553

Term of patent 14 years

(Cl. D4—4)

To all whom it may concern:

Be it known that I, Raymond J. Stewart, a citizen of the United States, residing at Miami, in the county of Dade and State of Florida, have invented a new, original, and ornamental Design for a Tile Wall Unit for Swimming Pools, of which the following is a specification, reference being had to the accompanying drawing forming a part thereof.

Fig. 1 is a top perspective view of a swimming pool, showing my new design, it being understood that the tile arrangement shown in solid lines is repeated throughout the unit;

Fig. 2 is a top plan view of a segment of the wall unit of Fig. 1;

Fig. 3 is a front elevational view of the segment shown in Fig. 2;

Fig. 4 is a side elevational view of the segment shown in Fig. 2; and

Fig. 5 is a back elevational view of the segment shown in Fig. 2.

The essential features of my design are shown in full lines.

I claim:

The ornamental design for a tile wall unit for swimming pools, as shown and described.
